AWNING

Frank A. Powell, Collingswood, N. J.

Application April 8, 1949, Serial No. 86,217

6 Claims. (Cl. 160—45)

1

My invention relates to new and useful improvements in awnings especially that type generally referred to as sunshades because of their simplicity, relative lightness and ease of operation.

One object of the invention is inexpensiveness of construction.

Another object of this invention is to provide improved means for connecting the fabric with the window frame.

Another object of the present invention is to construct an awning frame of three rods detachably connected together whereby the entire device can be shipped or stored in knock-down condition.

A further object of the invention is to provide an awning comprising, in combination, a pair of identical brackets, a frame consisting of side rods and a cross rod detachably connected together, and a fabric top, said side rods being detachably mounted in the brackets by pivot pins and the frame being retained in raised or lowered positions under tension provided by the fabric top in association with a window frame and holding pins selectively mounted in the brackets in opposition to the lines of force caused by the tension of the fabric top.

A still further object of the invention is to utilize identical brackets for hanging the frame, each bracket consisting of a back with upper and lower ears, and a pair of spaced parallel forwardly projecting wings having pairs of aligned apertures, the lower pair of apertures receiving a pivot pin and the other pairs of apertures adapted to receive a holding pin selectively positioned in either of said other pair.

Still another object of the invention is to provide means for holding the awning frame and fabric top in either a raised or lowered position without the use of a rope and cleat, the parts hereof being so arranged and located relative to one another that the structure is both non-rattling and wind resisting in either the operative or inoperative positions.

With the above and other objects in view this invention consists of the details of construction and combination of elements hereinafter set forth and then designated by the claims.

In order that those skilled in the art to which this invention appertains may understand how to make and use the same I will describe its construction in detail, referring by numerals to the accompanying drawing, forming a part hereof, in which:

Fig. 1 is a perspective view of an awning structure constructed in accordance with my invention and shown associated with a window frame in a raised or inoperative position.

Fig. 2 is a similar view with the awning in a lowered or operative position and a portion of the fabric broken away to show the frame cross rod.

Fig. 3 is an enlarged side elevation of a bracket

2

with a portion of its associated side rod pivoted therein and shown in the raised position and illustrating in dotted lines the lowered position of said side rod.

5 Fig. 4 is a perspective view of a bracket.

Fig. 5 is a broken sectional view of the joint between one of the side rods, the inner end of which is shown in elevation, the cross rod and the connection of the fabric top to the frame rods.

10 Fig. 6 is a fragmentary perspective view of the inner end of a side rod.

Fig. 7 is a fragmentary view of one side rod and the cross rod in the region of their joint but in separated relation.

15 In carrying out my invention as herein embodied 10 represents a pair of identical brackets each comprising a back 11 with a pair of spaced forwardly projecting wings 12 extending from opposite side edges thereof. Preferably said back extends above and below the locations of the wings to define ears 13 having holes 14 therein to receive suitable fastening devices, such as screws, for securing brackets to the sides 15 of 20 the window frame 16.

25 The awning frame consists of a cross rod 17, Fig. 5, and two identical side rods 18. The cross rod is notched and slightly flattened adjacent both ends and the side rods also are notched 30 and slightly flattened adjacent their outer ends so that the several rods nest into one another at their joints with a suitable fastening device 19 passing through the cross rod and a side rod at each joint. Such a fastening device is shown as 35 a bolt 20 projected through holes in the rods with a nut 21 screwed onto said bolt.

The inner end of each side rod 18 is flattened to provide a bearing 22 with a hole 23 there-through which inner end is projected into the

40 space between the wings of a bracket until the hole 23 is in alignment with the pair of aligned lowermost apertures 24 in the wings of the bracket. With the parts thus positioned, a pivot pin 25, such as a cotter pin, is inserted through 45 the apertures and hole to pivot a side rod to its respective bracket. When both side rods are thus mounted the awning frame is swingingly or hingedly assembled for up and down movements in the arc of a circle.

50 The fabric top 26 is secured at its upper end to the top member 27 of the window frame 16 by fastenings 28 and generally includes a body section, which is inclined when the awning is lowered, and a depending apron. On the inside of

55 the fabric top, adjacent the line of demarcation between the body and apron, is secured a transverse strip 29 of fabric which, with the cooperating part of the fabric top, forms a pocket or tunnel 30 into which the cross rod 17 is slid prior to the latter being attached to the side rods. The top proper and the fabric strip have holes to receive the projecting ends of the side rods and these holes are reinforced by eyelets or grommets

31 which tightly fit the projecting ends of the side rods, requiring some force to place them over and remove them from said side rods.

When the awning is raised both side rods will be substantially vertically positioned, shown in full lines in Fig. 3, and holding pins 32 are inserted in the uppermost pairs of aligned apertures 33 in the wings of both brackets so as to be located in front of the side rods relative to the outward and downward paths of travel of said side rods. The pocket strip and eyelets provide extra layers of materials so that when they coat with the window frame some outward tension is exerted on the awning frame and it is necessary to slightly compress the materials as the holding pins are inserted in their respective pairs of apertures 33.

To lower the awning, the holding pins 32 are removed from the pairs of apertures 33 and the frame pulled downwardly and outwardly until the side rods reach the approximate position indicated in dotted lines in Fig. 3 at which time the holding pins 32 are inserted in the pairs of aligned apertures 34 in the wings of the brackets. The apertures 34 are so located that the awning top has to be pulled quite taut to allow the holding pins to be inserted behind the side rods. Therefore in the lowered position there also is some tension exerted upon the awning frame.

As the awning frame is under tension by the awning top, both in its raised and lowered positions, when the holding pins are in place, the awning is highly wind resistant and non-rattling.

Of course I do not wish to be limited to the exact details of construction herein shown and described as these may be varied within the scope of the appended claims without departing from the spirit of my invention.

Having described my invention what I claim as new and useful is:

1. In an awning, the combination with a window frame, of a fabric top having one end attached to the upper portion of said window frame, an awning frame to which the other end of the fabric top is attached, said awning frame including side rods, brackets secured to the window frame and each having a plurality of pairs of apertures, a pivot pin inserted into a certain pair of said apertures and through the associated side rod of the awning frame for swingingly mounting the latter, and a holding pin selectively inserted in any of the remaining pairs of said apertures to retain the awning frame in a selected position with relation to the brackets, the fabric top being held under tension by said awning frame when said holding pin is in a certain pair of the other apertures and the awning frame is retained against said holding pin.

2. The awning structure according to claim 1 wherein the awning frame consists of the side rods each having a slightly flattened and notched portion adjacent the outer end, a cross rod having slightly flattened and notched portions adjacent the ends, said rods being nested at the notched locations, and separable fastening means detachably connecting the nested portions.

3. In an awning bracket, the combination of a pair of identical parallel spaced wings having a plurality of pairs of apertures, one aperture of each pair being in a separate wing, a rod having an end inserted between said wings and provided with a hole to align with a certain pair of said apertures, a pivot pin extending through the hole and the apertures with which said hole is aligned, and a holding pin selectively inserted into any of

the remaining pairs of apertures to retain said rod in various positions relative to said bracket.

4. The combination of a bracket comprising a back, and a pair of identical wings projecting from said back, said wings having a plurality of pairs of aligned apertures, a rod having an end projected between said wings and provided with a hole to align with a certain pair of said apertures, a pivot pin extending through said hole and the aligned apertures, and a holding pin selectively insertable in any of the other pairs of apertures for cooperation with the rod to retain the latter in a selected position.

5. The combination of a bracket comprising a back having ends provided with ears, said ears having apertures to receive fastening devices, and wings projecting from said back in spaced parallel relation and located between the ears, said wings having three pairs of aligned apertures, one pair being adjacent the lower edges of the wings, another pair being adjacent the upper edges of said wings and in a vertical plane slightly forward of a vertical plane intersecting the lower pair of apertures, and the other pair being intermediate the first two mentioned pairs and forward thereof, with a rod having an end projected between the wings and provided with a hole aligned with the lower pair of wing apertures, a pivot pin extending through the hole in the rod and said lower pair of wing apertures to pivotally mount said rod, and a holding pin selectively insertable in either of the other pairs of wing apertures to retain the rod in various adjusted positions relative to the bracket.

6. In an awning, the combination with a window frame, of a fabric top having one end attached to the upper portion of said window frame, an awning frame to which the other end of the fabric top is attached, said awning frame including side rods and a cross rod connected to said side rods adjacent their outer ends leaving the extremities free and projecting through the awning top, brackets secured to the window frame and each having a plurality of pairs of apertures, one pair of which receives a pivot pin also passing through the associated side rod of the awning frame for swingingly mounting the latter, another pair of said apertures adapted to receive a holding pin and located above and in a vertical plane slightly forward of the plane of the pivot pin receiving apertures whereby a holding pin may be positioned in front of the side rod to temporarily retain the awning frame in a raised position in close proximity to the window frame, and means surrounding each side rod of the awning frame for securing the awning top fabric to said awning frame and engaging the window frame when said awning frame is in the raised position to impart a tension on the awning frame against each holding pin.
